UNITED STATES PATENT OFFICE.

WILLIAM H. YOUNG, OF TROY, NEW YORK.

DESIGN FOR A MONUMENT.

SPECIFICATION forming part of Design No. 27,115, dated May 25, 1897.

Application filed February 12, 1897. Serial No. 623,190. Term of patent 14 years.

To all whom it may concern:

Be it known that I, WILLIAM H. YOUNG, a citizen of the United States, residing at the city of Troy, in the county of Rensselaer and State of New York, have invented and produced a new and original Design for a Sarcophagus Monument, of which the following is a specification, reference being had to the accompanying drawings.

10 Figure 1 of the drawings is a view in side elevation of a monument embodying my new design. Fig. 2 is a top plan view of the same.

The leading feature of the design consists in the ornamental configuration of the die.

15 Referring to the drawings, A is the lower, and A' the upper, base. Upon the upper base rests the die B, which is surmounted by the cap C. The general form of these members, as seen in plan, is rectangular, with two elongated sides, as shown in Fig. 2. The vertical sides of the bases and die exhibit uncut rock, or what is known as "rockwork." One or both of the longer vertical sides of the die are ornamented with a hammered or polished

25 tablature D, in the form of a central arch extending nearly to the top of the side, leaving

above the tablature a projecting tablet of rockwork D', extending across the upper side of the die, comparatively narrow at the middle of the side and gradually increasing in width toward each end.

Upon the face of the tablature may be placed an arched tablet E, having its upper and lower border-lines parallel with the border-line of the arch of the tablature.

I do not wish to be limited to a plane surface for the arched tablet, as the same may be cut to form special designs within my general design.

The arched tablet may be either intaglio or 40 relief.

What I claim as new, and desire to secure by Letters Patent, is—

The design for a monument herein shown and described.

In testimony whereof I have hereunto set my hand this 10th day of February, 1897.

WM. H. YOUNG.
